IRONING TABLE HAVING FOLDING SUPPORTS

Christ Tonn, Minneapolis, Minn., assignor to H. V. Keller Manufacturing Co., Minneapolis, Minn., a corporation of Minnesota

Application June 8, 1945, Serial No. 598,282

7 Claims. (Cl. 38—117)

1

This invention relates to ironing tables.

The present invention shows an arrangement wherein a locking brace extends across a portion of the front leg unit when the table is collapsed. By so arranging the structure it is possible to open the table from its collapsed position by pressure exerted on the front leg, such pressure being transmitted through the locking brace to the rear leg assembly and thereby greatly facilitating the setting up of the table.

In the present invention it is an object to provide a locking brace arrangement wherein said brace extends not only across the front leg unit but also across the front leg brace which is connected between the front and rear legs, thereby producing an even smoother acting movement of the legs and braces when the table is set up.

Another object of the invention is to arrange the locking brace across the front leg and front leg brace as described above and to connect the locking brace and front leg brace to the rear leg unit at spaced points so that the opening force derived from pressure on the front leg unit will be transmitted to the rear leg unit in more than one point thereby facilitating the opening action and also producing a more rigid and stable construction.

Another object of the invention is to provide an improved mounting plate by means of which the leg units are pivotally connected with the top and also to provide an advantageous latching and setting means for the ends of the locking brace when the table is set up for use.

These and other objects and advantages of the invention will more fully appear from the following description made in connection with the accompanying drawings, wherein like reference characters refer to the same parts throughout the views, and, in which:

Figure 1 is a side elevation of the table in position for use;

Figure 2 is a bottom plan view thereof with the leg and brace structures in their collapsed positions;

Figure 3 is a rear elevation of the table in its operative position;

Figure 4 is an enlarged fragmentary sectional view through the locking brace catch;

Figure 5 is an enlarged fragmentary sectional view taken approximately on the line 5—5 of Figure 2; and

Figure 6 is an enlarged plan view of the rear leg mounting plate.

In the drawings there is shown a front leg unit 7 having a pair of arms which diverge upwardly

2

and rearwardly whose upper ends are pivotally connected to lugs or ears 8 which are struck from a front leg mounting plate 9 extending across the underside of the table top 10 and secured to said table top by suitable means such as rivets 11.

Rear legs 12 are pivotally connected to lugs 13 which are struck from a rear leg mounting plate 14 secured to the underside of the top 10 by rivets 15. Rear leg braces 16 have their lower ends connected to the rear legs 12, as shown, at 17, and the upper ends of braces 16 are pivotally connected to lugs 18 struck from the rear leg mounting plate 14.

A front leg brace is made up of a pair of upwardly and rearwardly divergent arms 19, said front leg brace being connected to the lower end of the front leg unit 7, as shown in Figures 1 through 3, and the rear ends of the front end brace unit 19 are pivotally connected to the rear legs 12 as shown at 20.

A locking brace unit 21 has downwardly and rearwardly divergent arms which are pivotally connected to the rear legs 12 at points 22, which are considerably lower on the rear legs 12 than the pivot points 20 of the front leg brace 19.

The upper forward portion of the locking brace 21 lies beneath a guide 23 which extends a substantial distance along the underside of the table top 10 and which permits the forward end of the locking brace 21 to describe limited sliding movement relative to the top 10.

Mounted on the rear portion of the guide 23 is a locking brace catch 24 which has a pivot pin 25, the latter being secured to the guide 23 by a clip 26 which in turn is secured to said guide 23 by a rivet 27. A leaf spring 28 has one end secured to the guide 23 by a rivet 29 and the other end of said spring 28 bears against the catch member 24 normally urging it up against the front leg mounting plate 9 to releasably secure the locking brace 21 in the manner best shown in Figure 4. The catch 24 is conveniently released by a lever 30 which is pivotally mounted on a small bracket 31 on the underside of the top, between the front leg mounting plate 9 and the rear leg mounting plate 14. The lever 30, as shown in Figure 2, is in the form of an elongated loop throughout approximately its rear half, and this looped portion of the lever 30 extends between and beneath a pair of lugs 32 which are struck from the rear leg mounting plate 14 adjacent the central portion thereof. Lugs 32 serve as a guide and movement limiting means for the catch release lever 30.

From the foregoing description it is believed

that the structure and function of the ironing table are fairly obvious. It should be noted, however, that when the board is in the collapsed position of Figure 2 the front legs 7 and front leg brace 19 are substantially nested and practically flat against the table top with the diverging arms of said front arm and said front leg brace in approximately the same plane. It should also be noted that the locking brace 21 has its arms converging forwardly from the pivot point 22 on the rear legs and that the two arms of the locking brace 21 overlie the adjacent arms of the front leg 7 and front leg brace 19. As a result, when the front leg is grasped and pulled outwardly from the underside of the table top, pressure is exerted against the locking brace and transmitted therethrough to the rear legs. At the same time force is exerted directly by the front leg brace 19 to the rear legs 12. This close association and contact between adjacent portions of the legs and braces makes the structure one which is extremely easy to open without forcing or bending any of the leg and bracing structure such as so frequently occurs in ironing table constructions.

As the legs and braces swing to their set up position the front leg brace 19 straddles the locking brace 21 remaining in contact therewith. The normal resilience of the middle bars which make up the front leg bar 19 and locking brace 21 thereby produce a gripping action which considerably strengthens and aids rigidity to the table assembly but at the same time permitting the members 19 and 21 to slide freely relative to each other when the table is collapsed and set up.

Attention is also called to the spaced location of the pivots 20 and 22 for the leg brace 19 and locking brace 21 respectively. The spacing of said pivots 20 and 22 permits the application of opening force at different points on the rear legs 12 to facilitate opening movement and prevent strain on the pivots and, of course, it creates a more rigid table construction.

The particular leg mounting plates and the locking brace catch mechanism are simple yet highly efficient structures which add to the general advantages of the table.

It will, of course, be understood that various changes may be made in the form, details, arrangements and proportions of the various parts without departing from the scope of my invention.

What I claim is:

1. In an ironing table, a top assembly, a front leg unit movably connected to said top assembly, a rear leg unit movably connected to said top assembly, a front leg brace movably connected to said front leg unit below the upper end thereof and also movably connected to said rear leg unit below its upper end, and a locking brace having an end movably connected to the under side of said top assembly for movement longitudinally of said top assembly and parallel thereto and extending downwardly and rearwardly and being movably connected to said rear leg unit a substantial distance below the connection of said front leg brace and said rear leg unit.

2. The structure in claim 1, and said leg units,

front leg brace and locking brace being collapsible toward the underside of said top assembly, and when collapsed, a portion of said locking brace per se lying at an angle to and crossing and overlying said front leg unit.

3. The structure in claim 1, and said front and rear leg units, said front leg brace, and said locking brace being collapsible toward the underside of said top assembly, and when collapsed, a portion of said locking brace per se crossing and overlying said front leg unit and said front leg brace at an angle thereto.

4. In an ironing table, a top assembly, a front leg unit pivotally connected to said top assembly, a rear leg unit pivotally connected to said top assembly, a front leg brace movably connected to said front leg unit below the upper end thereof and also movably connected to said rear leg unit, a locking brace movably connected to the underside of said top assembly and extending downwardly and rearwardly and being movably connected to said rear leg unit, said front and rear leg units, front leg brace and locking brace being collapsible from the underside of said top assembly, and when so collapsed, a portion of said locking brace per se lying at an angle to and crossing and overlying said front leg unit and said front leg brace.

5. In an ironing table, a top assembly, a front leg unit pivotally connected to said top assembly, a rear leg unit pivotally connected to said top assembly, a front leg brace movably connected to said front leg unit below the upper end thereof and movably connected to said rear leg unit, a locking brace having an end movably connected to the underside of said top assembly and extending downwardly and rearwardly and movably connected to said rear leg unit, said leg units and braces being shiftable toward and away from said top assembly to collapsed and set-up positions, and said locking brace and said front leg brace having portions contacting each other in their set-up position, and said locking brace having a portion thereof crossing and overlying said front leg brace in the collapsed positions of said braces.

6. The structure in claim 5, and said locking brace crossing and overlying said front leg brace through the initial movement of said braces from their collapsed positions to their set-up positions.

7. The structure in claim 5, and said locking brace having a portion thereof also crossing and overlying said front leg unit in the collapsed positions of said front leg unit and locking brace.

CHRIST TONN.
